UNITED STATES PATENT OFFICE

2,358,333

MOVABLE DEMOUNTABLE SCAFFOLD SUPPORT

James Cleveland King, Lake Wales, Fla.

Application April 17, 1943, Serial No. 483,382

2 Claims. (Cl. 304—32)

This invention relates to movable, demountable scaffold supports.

An object of the invention is to provide a scaffold of the character described which may be made of six pieces of wood and two fillers, and which shall be strong and durable and which can be collapsed and set up easily.

A further object of this invention is to provide a triangular scaffold of the character described, which may be used side by side to support a catwalk or one above the other, which comes in contact with the wall.

Yet another object of this invention is to provide a strong and durable scaffold of the character described which shall be relatively inexpensive to manufacture, easy to assemble, and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing in which is shown one of the various possible illustrative embodiments of this invention,

Fig. 1 is a perspective view of a scaffold embodying the invention, with an additional optional part shown in dotted lines;

Fig. 2 is a top plan view of the improved scaffold;

Fig. 3 is a side elevational view of the scaffold; and

Fig. 4 is a side elevational view showing a pair of scaffolds used one above the other.

Referring now in detail to the drawing, 10 designates a triangular scaffold embodying the invention. The same comprises a vertical board or piece of wood 11. The piece 11 has a horizontal and forwardly inclined upper edge 11a, and a forwardly and upwardly inclined lower edge 11b. Said piece 11 is formed with a mortise groove 12 at the top thereof midway between the side faces of said piece.

Received in said mortise is the rear end 13 of a horizontal piece 14 preferably of hardwood, Norway or Southern Yellow Pine of clear straight grained stock. This piece is placed edgewise in the mortise 12 of the vertical piece 11 which comes in direct flat contact with the wall or building to which the scaffold is attached. It must sustain the required number of workmen and material, it being understood however that 55

the scaffolds 10 are placed as close together as desired. Piece 14 extends forwardly from the upper end of member 11. On the opposite sides of member 14 are parallel filler boards 15 the rear ends whereof contact the front edge of member 11 on both sides of the mortise 12. The combined thickness of members 15, 14 is preferably equal to the thickness of member 11. Members 14, and 15 have downwardly and rearwardly inclined coplanar forward edges 18.

Interconnecting the forward ends of members 14, 15 with the lower end of member 11 are a pair of parallel boards 19 contacting the outer faces of members 15 and 11. The upper and lower ends of members 19 are flush with the upper edges, of members 14, 15, and of the rear face of member 11, respectively.

There is further provided a pair of parallel braces 20 interconnecting vertical member 11 with members 14, 15. Members 20 are parallel to members 19, and contact the outer faces of vertical member 11, at their lower ends, and the outer faces of filler members 15 at their upper ends. Filler members 15 are preferably formed with shallow grooves 15a to receive portions of members 20, and member 11 is likewise formed with similar grooves 20a to receive portions of members 20. The lower end edges of members 20 are flush with the rear edge of member 11. The upper end edges of members 20 are flush with the upper edges of members 14, 15.

Member 14 is attached to member 11 by a plurality of bolts 25 provided with wing nuts. Members 14, 15 are attached to the upper ends of members 18 by bolts 26 provided with wing nuts. The lower ends of members 19 are fixed to the lower end of member 11 by a plurality of bolts 27 provided with wing nuts.

The upper and lower ends of members 20 are attached to members 14, 15 and 11 respectively by bolts 29 and 30 also provided with wing nuts.

By removing the bolts aforementioned, all the parts of the scaffold can be collapsed.

An additional diagonal strut or brace 40 may be provided if desired. This brace may extend from the upper rear corner, downwardly and forwardly and be attached to members 20 and 19 in any suitable manner.

In Fig. 4 a pair of scaffolds are shown one above the other with a cleat 42 therebetween.

It will thus be seen that there is provided a device in which the several objects of this invention are achieved and which is well adapted to meet the conditions of practical use.

As various possible embodiments might be

made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:

1. A scaffold comprising a vertical member having a mortise at its upper end, a horizontal member having the rear end received in said mortise and extending forwardly therefrom, means to attach the upper end of the vertical member to the rear end of the horizontal member, a pair of filler boards on opposite sides of said horizontal member, a pair of parallel, forwardly and upwardly inclined boards extending from the lower end of said vertical member to the forward ends of said filler boards, and contacting the outer faces of said vertical member and filler members, respectively, means to attach the upper ends of said inclined boards to the horizontal member and filler boards, means to attach said inclined boards to said vertical board, a pair of parallel braces, interconnecting the midportion of said vertical member with the midportions of said horizontal member and filler boards, said filler boards and vertical member having grooves in the outer faces thereof to receive portions of said braces.

2. A scaffold comprising a vertical member

having a mortise at its upper end, a horizontal member having the rear end received in said mortise and extending forwardly therefrom, means to attach the upper end of the vertical member to the rear end of the horizontal member, a pair of filler boards on opposite sides of said horizontal member, a pair of parallel, forwardly and upwardly inclined boards extending from the lower end of said vertical member to the forward ends of said filler boards, and contacting the outer faces of said vertical member and filler members, respectively, means to attach the upper ends of said inclined boards to the horizontal member and filler boards, means to attach said inclined boards to said vertical board, a pair of parallel braces, interconnecting the midportion of said vertical member with the midportions of said horizontal member and filler boards, said filler boards and vertical member having grooves in the outer faces thereof to receive portions of said braces, the upper end edges of said inclined boards and braces being flush with the upper edges of said horizontal member and filler boards, and the lower end edges of said inclined boards and braces being flush with the rear edge of said vertical member, the thickness of said vertical member being equal to the combined thickness of said horizontal member and filler boards.

30

JAMES CLEVELAND KING.
